(57) **CLAIM**

The ornamental design for a two-point control leash for dog, as shown and described.

DESCRIPTION

FIG. 1 is a top, front, right side perspective view of a two-point control leash for dog, showing my new design; FIG. 2 is a bottom, rear, left side perspective view thereof; FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged top view thereof; and,

FIG. 10 is an enlarged bottom view thereof.

The evenly dotted broken lines depict stitching of the two-point control leash for dog and form no part of the claimed design.

1 Claim, 10 Drawing Sheets
